(57) **CLAIM**

The ornamental design of a disc golf target, as shown and described.

DESCRIPTION

FIG. 1 is a perspective view of a disc golf target showing my new design, shown in its flat position;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a perspective view thereof, shown in its cylindrical position;

FIG. 9 is a front elevational view of FIG. 8;

FIG. 10 is a rear elevational view of FIG. 8;

FIG. 11 is a right side elevational view of FIG. 8;

FIG. 12 is a left side elevational view of FIG. 8;

FIG. 13 is a top plan view of FIG. 8; and,

FIG. 14 is a bottom plan view of FIG. 8.

The broken lines illustrating the interlocking tabs form no part of the claimed design. The remaining broken lines including the representing logos form no part of the claimed design.
